UNITED STATES PATENT OFFICE.

HORACE SEE, OF PHILADELPHIA, PENNSYLVANIA, ASSIGNOR OF ONE-HALF
TO THE WILLIAM CRAMP & SONS SHIP AND ENGINE BUILDING COMPANY, OF SAME PLACE.

STEAM-ENGINE.

SPECIFICATION forming part of Letters Patent No. 252,267, dated January 10, 1882.

Application filed October 29, 1881. (No model.)

To all whom it may concern:

Be it known that I, HORACE SEE, of the city and county of Philadelphia, in the State of Pennsylvania, have invented certain new and useful Improvements in Steam-Engines, of which improvements the following is a specification.

My invention, having been especially designed for use in vertical direct-acting marine steam-engines of the "tandem" compound type, will be herein described and shown as applied to an engine of such description, but certain of its features are, as will hereinafter appear, equally applicable to steam-engines of different construction.

The objects of the invention are to provide simple and effective means for connecting the piston-rod of the low-pressure cylinder to its piston and to the piston-rod of the high-pressure cylinder; to provide steam reversing mechanism of improved construction, and to so combine the same with other portions of the structure as to effect an economy of space and admit of convenient access to working parts, and to afford improved facilities for applying and operating a steam-cylinder independent of the main engine, to wholly or partially rotate the crank-shaft.

To these ends my improvements consist in certain novel devices and combinations hereinafter fully set forth.

In the accompanying drawings, Figure 1 is an end view, in elevation, of a vertical direct-acting engine embodying my invention; Fig. 2, a side view, in elevation; and Fig. 3, a horizontal section at the line $x-x$ of Fig. 1 of the same; Fig. 4, a sectional elevation of the high and low pressure piston-rods and their connections; Fig. 5, a transverse section at the line $y-y$ of Fig. 4; Figs. 6 and 7, plan and side views respectively of the nut of the high-pressure piston-rod; Fig. 8, a side view, partly in section, of the independent turning engine; Figs. 9 and 10, plan and end views respectively of the same; and Fig. 11, a view in perspective showing the pawls of the turning-gear.

The high and low pressure cylinders 1 2 are located in line vertically above the frames or

50 housings 3, the high-pressure cylinder being supported upon columns 4 5 at such distance above the low-pressure cylinder as to enable the piston of the latter to be conveniently removed when required. The main distribution-valves of the two cylinders are operated by eccentrics 6, the rods 7 of which are connected 55 to the valve-link 8 by the movements of which the valves are reciprocated. The cut-off valve of the high-pressure cylinder is worked by a separate eccentric and curved arm admitting of variations, as desired, in the grade of expansion. The steam exhausted from the steam-chest of the low pressure passes through the exhaust-pipe 9 to the condenser 10. The air-pump, circulating-pump, and sundry other details of the mechanism not comprehended within my present invention are for greater clearness omitted from the drawings.

60 In engines of the type herein shown and described it is of material importance that the rods of the high and low pressure pistons 70 should be set and be maintained truly in line, that they should be firmly connected one to the other, and that facilities should be provided for the removal of the low-pressure piston, when required, without removing or disturbing the attachments of the high-pressure cylinder. These objects I attain by the construction shown in Figs. 1 to 7, inclusive, referring to which the manner of connecting the rods will be plainly seen. The high-pressure 80 piston-rod 11 has a collar, 12, formed upon it adjacent to its lower end, and the rod is tapered inwardly, or of frusto-conical form, from the collar 12 to said lower end. The tapered portion 13 of the rod fits within a corresponding 85 central bore or recess in the upper end of the low-pressure piston-rod 14, the taper of the meeting surfaces serving to guide and center the high-pressure rod accurately in line with the axis of the low-pressure rod. A male 90 thread, 15, is cut upon the periphery of the rod 14 from its upper end to a point below the bottom of the recess which receives the rod 11, and the rod 14 is tapered outwardly from the bottom of the thread 15 to a collar, 16, which 95 forms the bearing to receive the low-pressure

piston 17, said piston being secured in position by an internally-threaded sleeve or nut, 18, engaging the thread 15 and clamping the piston between its lower face and the collar 16. The 5 rod 11 is fixed in its bearing in the rod 14 by an externally-threaded sleeve or nut, 19, divided vertically into two halves, so as to permit of its insertion and removal, said halves being connected by pins or screws 20. The 10 nut 19 fits accurately around the rod 11, and its thread engages that of the nut 18, so that when screwed to a proper bearing upon the collar 12 it connects the rods 11 and 14 firmly together, while admitting of their ready separation whenever required. Set-screws 21 22 prevent the slackening of the nuts 18 and 19, respectively, when the same are adjusted in position. A collar, 23, adjacent to the upper end of the rod 11, forms the seat or bearing for 20 the high-pressure piston 24, which is secured in position by a nut, 25, and the cross-head 26 is similarly clamped against a shoulder on the low-pressure rod by a nut. Divided bushings are employed in the glands between the high 25 and low pressure pistons, by the removal of which and of the nut 19 the high-pressure piston and rod may be removed through the upper end of its cylinder whenever desired.

The valve-link 8 and the connected distribution-valves of the high and low pressure cylinders are shifted in position, as required for stopping, starting, and reversing the direction of movement of the crank-shaft 28, by a steam reversing-cylinder, 30, fitted with a proper piston and steam-valve, which latter is operated by hand through a lever, 31, journaled in a stand or bearing, 32, on one of the housings 3.

In order to simplify the construction and operation of the reversing mechanism, and to 40 so locate it that it shall be conveniently accessible to the engineer, and be, as far as practicable, removed from interference with other members of the engine, the reversing-cylinder 30 is arranged substantially in line horizontally with the link 8, when the latter is in the position which it occupies when the crank 45 29 is upon either of its centers, and is supported upon the exhaust-pipe 9, which is recessed transversely, as shown in Figs. 2 and 3, to enable the reversing-cylinder to be placed in line 50 vertically with the link, and to clear the adjacent operating-connection of the cylinder with the link. The reversing-cylinder 30 is bolted to the exhaust-pipe 9 through flanges abutting 55 against corresponding bearing-surfaces on the exhaust-pipe above and below the recessed portion thereof, at which portion the exhaust-pipe is expanded transversely, as seen in Figs. 1 and 3, to prevent the reduction of its sectional area which would otherwise be incident to recessing it. The piston-rod 33 of the reversing-cylinder passes through a proper stuffing-box at the outboard end of the cylinder, and is secured to a cross-head, 34, working in 60 guides 35. The cross-head 34 is coupled by a pair of connecting links or bars, 36, to pins or

wrists 37 on the sides of the valve-link 8, and the movements of the piston of the reversing-cylinder are thus communicated directly to the valve-link, and transmitted thereto, as nearly 70 as may be, in right line, eliminating the rock-shafts and other intermediate mechanisms heretofore employed, and inducing a corresponding advantage in economy of construction and facility of operation. The valve-stem 75 of the reversing-cylinder is coupled by articulated links to the cross-head, so that while the opening movements of the valve are effected by hand the valve is closed automatically by the movement of the cross-head, so as to prevent jar or concussion by sudden termination 80 of the stroke of the piston.

The crank-shaft 28 may be rotated to any desired degree by an independent turning engine, the construction of which is shown in 85 Figs. 8 to 11, inclusive. The direct-acting steam-cylinder 38 of the turning engine is fitted with a piston, 39, secured upon a rod, 40, the outer end of which carries a cross-head, 41, to which pawls 42 and 43 are pivoted, said 90 pawls engaging ratchet-teeth 44 and 45, respectively, on the periphery of a balance-wheel, 46, secured upon the crank-shaft 28 adjacent to and in rear of the main engine. The central series of ratchet-teeth, 44, with which the 95 pawl 42 is adapted to be engaged, extend in reverse direction to the two side series of ratchet-teeth, 45, with which the pair of pawls 43 may be engaged, the crank-shaft being thus capable of movement in one or the other direction, according as the pawl 42 or the pawls 43 are employed to transmit to it the movement of the piston 39. The piston-rod 40 is prolonged beyond the cross-head 41, its extension 47 being flattened or squared on one side, and 100 fitted to slide in a guide or bearing, 48, secured upon one of the housings, a gib, 49, being placed in the bearing 48 as a guide for the flattened portion of the rod. Springs 50 51 at each end of the extension 47 serve a cushioning 105 purpose to prevent undue jar against the guide 48 when the piston reaches the extremities of its stroke. A rock-shaft, 52, is mounted in a bearing, 53, on the cross-head 41 at right angles to the piston-rod 40, from which rock-shaft two arms, 54 110 55, project in opposite directions. One of the arms, 54, is connected by a link, 56, to the central pawl, 42, and the other, 55, is similarly connected by a link, 57, to the side pawls, 43, so that by the vibration of the rock-shaft either 115 the pawl 42 or the pawls 43 may respectively be engaged with the corresponding series of ratchet teeth of the balance-wheel 46, or all the pawls be held out of contact with the teeth, as desired. The rock-shaft 52 is vibrated by a 120 hand-lever, 58, mounted in a stand, 81, located upon the working-platform of the engine, the lever 58 having an arm, 59, connected by a link, 60, bell-crank 61, and link 62, with an arm, 63, on a shaft, 64, which is mounted, so as to be 125 capable of free rotation in a bearing, 65, formed in an extension of the rock-shaft bearing 53 on 130

the cross-head 41, while accompanying said cross-head in its reciprocating movements. An arm, 68, on the shaft 64 is coupled by a link, 66, to the arm 55, so that when the shaft 64 is 5 vibrated by the hand-lever 58 and its connections it imparts corresponding movement to the rock-shaft 52 and establishes connection of the desired pawl or pawls with the balance-wheel, or withdraws the pawl or pawls therefrom, as the case may be. The shaft 64 passes 10 through and is guided by a bearing, 67, on the cylinder 38, and it will be obvious that it must be connected with the arm 63 through the intermedium of a feather and spline, so as to 15 be free to move longitudinally in the hub of said arm, while compelled to follow the vibrations thereof about the shaft 64 as a center. The link 66 must further be provided with suitable gimbal or universal joints at its ends to 20 enable it to conform to the arcs described by the arms 55 and 63 in the traverse thereof induced by the movements of the hand-lever 58.

The steam-valve 69 of the turning cylinder 25 38 is operated by a hand-lever, 70, mounted in the bearing 81 of the pawl-lever 58, concentrically with the latter, and having an arm, 71, connected by a link, 72, double-armed rocking lever 73, link 74, rock-shaft 82, and arms 75 30 83, and links 76 77, with the valve-stem 78. The link 77 is coupled by a link, 79, to a stud, 80, on the cross-head 41, so that the valve 35 will be closed automatically by the movement of the cross-head, for the purpose of cushioning the piston at the ends of its stroke in a similar manner to the valve of the reversing-cylinder hereinbefore described. It will be observed that both the pawl and valve-gearing of the turning-engine are thus brought 40 within the control of the engineer by the manipulation of two levers located side by side in the same bearing, and that all portions of the turning mechanism are operated from a single stand-point.

I claim as my invention and desire to secure by Letters Patent—

1. In a tandem compound steam-engine, the combination, substantially as set forth, of a high-pressure piston-rod having a conical or tapered end and a collar adjacent thereto, a 50 low pressure piston-rod having a conical central recess to receive the end of the high-pressure piston-rod, and an external thread, a nut fitting the thread of the low pressure piston-rod and serving to clamp the piston thereof in 55 position, and a threaded sleeve engaging said nut and securing the high and low pressure piston-rods together through the nut of the latter.

2. In a direct-acting steam-engine, the combination, substantially as set forth, of a valve-link, a steam reversing-cylinder located substantially in line with said link when in the position corresponding to the termination of the

stroke of the engine-piston, and a pair of connecting links or bars by which the valve-link 65 and the cross-head of the reversing-cylinder are coupled directly together.

3. In a direct-acting steam-engine, the combination, substantially as set forth, of a valve-link, a steam reversing-cylinder located substantially in line with said link when in the position corresponding to the termination of the stroke of the engine-piston, and an exhaust-pipe which forms the standard or support of said reversing-cylinder. 75

4. In a direct-acting steam-engine, the combination, substantially as set forth, of a steam reversing-cylinder, and an exhaust-pipe which is recessed transversely adjacent to said cylinder and increased in width throughout said 80 recessed portion, said cylinder and exhaust-pipe being connected by flanges on each side of said recessed portion.

5. The combination, substantially as set forth, of a crank-shaft, a balance-wheel secured thereto and having series of ratchet-teeth formed in reversed directions upon its periphery, a direct-acting steam-cylinder having a piston-rod and cross-head traversing tangentially to said balance-wheel, pawls pivoted to 90 said cross-head and adapted to engage either of the series of ratchet-teeth of the balance-wheel, and a hand-lever connected to a rock-shaft by which either of the pawls may be engaged with or both disengaged from the teeth 95 of the balance-wheel.

6. The combination, substantially as set forth, of a crank-shaft, a balance-wheel secured thereto and having series of ratchet-teeth formed in reverse directions upon its periphery, a steam-cylinder adapted to operate pawls engaging one or the other of the series of ratchet-teeth of the balance-wheel, and a pair of hand-levers mounted adjacent one to the other in a stand or bearing upon the working-platform of the engine, said hand-levers operating respectively, the one to engage and disengage the pawls and ratchet-teeth and the other to move the valve of the steam-cylinder. 100 105

7. The combination, with the cross-head of a turning-engine, of pivoted pawls, a rock-shaft having arms projecting in opposite directions and connected by links with said pawls, a shaft moving with said cross-head and connected by a link with one of the arms of the rock-shaft, 110 and a hand-lever coupled to an arm on said longitudinally-moving shaft, the shaft and arm being connected through a feather and spline, so that the shaft shall partake of the vibrations of the arm and be allowed free longitudinal 115 movement within it, substantially as set forth. 120
